UNITED STATES PATENT OFFICE.

ARNALDO ROMUALDI, OF JERSEY CITY, NEW JERSEY, ASSIGNOR TO ROMUALDI MACHINERY & CONSTRUCTION CO., OF JERSEY CITY, NEW JERSEY.

AEROPLANE.

1,278,750.

Specification of Letters Patent. Patented Sept. 10, 1918.

Application filed January 4, 1916. Serial No. 70,294.

To all whom it may concern:

Be it known that I, ARNALDO ROMUALDI, a subject of the Kingdom of Italy, and resident of Jersey City, in the county of Hudson and State of New Jersey, have invented certain new and useful Improvements in Aeroplanes, of which the following is a specification.

This invention consists in constructing an aeroplane which derives sustentation from the combined pressures of the fluid it moves through, and by mechanical or other activity of the surfaces presented to the fluid.

15 The objects are:

To obtain lifting power in excess of that due to the velocity of the fluid.

To obtain inherent lateral stability.

To obtain variable lifting power.

20 To obtain lifting efficiency independent of the propelling apparatus.

To enable a flying machine to leave the ground after a short run, and to gradually land with propelling mechanism shut down.

25 To utilize the definite wave established by an advanced lifting unit, of applying in a short distance longitudinally by successive units conforming to said wave for incidentally increasing longitudinal stability.

30 To obtain for aeroplanes greater speed.

Drawings.

Figure 1 is a top plan view of an aeroplane constructed and arranged in accordance with the present invention;

35 Fig. 2 is a cross section on an enlarged scale, the section being taken as on the line 2-2 in Fig. 1;

40 Figs. 3 and 4 are cross sections of scale uniform with Fig. 2, showing modified forms of construction;

45 Fig. 5 is a diagram exemplifying the conditions which the herein described application of energy is intended to modify with levitating effect;

50 Fig. 6 is a top plan view on enlarged scale of a fragment of an aeroplane having levitating means constructed and arranged in accordance with a modified form of the invention;

Fig. 7 is a cross section taken on the line 7-7 in Fig. 6.

Description.

All throughout this paper the word "surface" is used to indicate the contact face of a body with the surrounding field and never in the sense of an aerial plane or other similar body of very small thickness relatively to its other dimensions as customary in aeronautical literature.

I consider three types of lifting units hereinafter called "elements" all founded on the same general principle and with a similar disposition of parts. The first is where the energy directly applied on the fluid is mechanical, the second is where mechanical and thermic or other form of radiant energy is applied simultaneously, and the third is where only such radiant energy is applied to the active surfaces.

The lifting unit which forms the fundamental part of this invention, is composed of a longitudinal frame carrying two fixed or revoluble members called hereafter "radiators", with axes parallel or at an angle with one another, the space between them being bridged to present upper and lower surfaces, for maintaining the difference in pressure resulting between the upper and lower streams into which the surrounding fluid is divided.

The lower surface extends between the two radiators from points in each taken on the sides facing each other at about thirty degrees below the geometrical plane containing the axes. It is generally curved away from the geometrical plane of the axes of the radiators, to guide the flow from the front to the rear radiator with minimum leakage around the revolving surfaces. The upper surface may extend from corresponding points in each radiator above the geometrical plane of their axes generally in a curved surface concave above as in Fig. 2, or in a concave or convex form extending between points at thirty degrees or more above said plane on the sides of the radiators facing each other. In Fig. 4 of the drawings is shown a preferred form of this construction.

A preferred form of embodiment of the present invention is shown in Figs. 1 and 2 of the drawings wherein rotary cylinders

9 and 10 are connected by fixed frames 11. The frames 11, as seen best in Figs. 2 and 3 of the drawings, have each a transverse brace 12. Each brace 12 supports the upper 5 cover plate 13 and the lower cover plate 14.

The ends of the cover plates 13 and 14 are connected by plates 15 having each extensions, wherein bearings 16 are formed for the axes 17 of the cylinders 9 and 10.

10 The axes 17 are each provided, at the inner end, with a suitable sprocket wheel for engagement by a sprocket chain 18. The chains 18 also engage sprocket wheels on a short intermediate driven shaft 19.

15 The shafts 19, as seen best in Fig. 1 of the drawings, have each a friction wheel 20, disposed at opposite sides of the driving shaft 21, and a driving disk 22 on shaft 21 driven by the aeroplane motor 23 is fur-

20 nished and on which a propeller 24 of conventional form is mounted. The friction wheels 20 are slidably mounted on their respective shafts 19, and are permanently disposed on a shifting plate 25, the movement 25 of which is controlled by a foot-operated lever 26 adjacent the aviator's seat 27.

From the foregoing it will be seen that when the aviator desires, he may, by moving the lever 26, shift the wheels 20 in opposite 30 directions relative to the center of the disk 22, thereby relatively increasing or diminishing the speed ratios of the wheels 20 at opposite sides of the disk 22. The change in speed ratio referred to correspondingly increases or diminishes, as the case may be, the rotary speed imparted to the cylinders 35 9 and 10, at opposite sides of the longitudinal axis of the aeroplane and thereby provides for the necessary differentiation in

40 levitation of the carrying members at opposite sides of the aeroplane to cant or tilt the same, as in banking, to alter the horizontal flight of the machine with or without the help of a steering rudder. The cylinders 45 rotate at equal speeds due to the connection by means of the chains 18.

The direction of rotation is the same for both the cylinder or the radiators. For sustentation the rotation is from below toward the front and then upward to the rear, as shown in Fig. 2. Reversing the direction of rotation may be resorted to for maneuvering, banking on a curve, or for rapid depression. The speed of rotation is 55 controlled by the pilot for varying the degree of sustentation, gaining or losing elevation according to the requirements of travel.

The cylinders may be shaped to any cross-section for best efficiency, and their outer surfaces may be smooth or grooved longitudinally, transversely or helicoidally. Also, they may have a fluted surface, projections or blades, straight or curved, to better conform with the flow around said cylin-

der, or to avoid leakage of fluid between the fixed and the revolving surfaces. They may be cylindrical or conical or built up of cylinders twisted together in the same relative position as the outer strands of a rope. 70

Modification.

A modified method for producing a radiating field around the cylinders or radiators is to supply heat or any suitable form of 75 radiant energy to the surfaces as fast as they radiate it into the enveloping medium. To that effect I provide, in Fig. 1, for the introduction of a heated medium, such as the exhaust from motor 23, with or without 80 addition of air, into or through the radiators 9 and 10, constructed of thin metal to allow rapid conduction of heat through the radiators' walls.

In the field of radiant energy thus obtained, the cylinder surface is again an equi-potential surface where the addition of the effect of its velocities with those of a parallel flow of the enveloping medium will take place along stream-lines as stated. Also in 90 the case of mechanically driven radiators, those portions of their surfaces immersed in the upper stream around an element are continuously cooled by the greatly increased 95 radiation from those surfaces, while the portions in contact with the lower stream are correspondingly heated from the increased pressure, the variation in heat energy at any instant on those portions of a cylinder's or radiator's surface represents the thermodynamical reactions from which the lifting effect 100 results.

An internal flow, therefore, taking the place in every way of mechanical drive of the radiator in an element, eventually adding lifting effect from its heat energy, I dispose (Fig. 6), a distributing box 100 inserted in the duct from the exhaust of the motor 23 to the radiators 9 and 10. This distributing box branches off in two separate pipes 101 and 102, through a differential valve 103, controlling the relative flow to either pipe which feeds into both radiators on one side of the longitudinal frame of the aeroplane. Whenever the pilot wishes to alter the lateral balance or steer the aeroplane, he can by this arrangement, vary the internal flow on the radiators of each element by moving valve 103 over the side which he intends to depress. In the 115 distributing box a cut-out valve 107 may be added, so that the pilot may allow some or all of the heated gases to escape to the atmosphere when required and thereby reduce the amount of heat applied and reduce the 120 elevation.

It is clear from the foregoing that the pilot on the aeroplane may open the cut-out valve, deriving sustentation on mechanical drive of the radiators, that is, with elements 130

of the first type; or may direct the exhaust gases in the radiators to take care of part of the drive, and derive further sustentation therefrom, thus obtaining elements of the 5 second type. He may control the lateral balance and steer by modifying either the mechanical drive or the internal flow, or both; by disconnecting the mechanical drive he might obtain both rotation of the radiators and direct sustaining power from the 10 internal flow, and, finally, if the radiators were fastened to the frame, get sustentation directly from the internal flow.

I provide a variation of profile such as 15 shown in Figs. 3 and 4, where the fixed radiators 28 and 29 in the shape of ducts of convenient shape and cross section as stated for revoluble radiators, are fastened to the plates 13 and 14, with the rivets 30, through 20 an interposed thickness 109 of other heat-insulating material.

In all elements supplied with heat, the upper cover plate 13 in Fig. 3, and the plate 31 in Fig. 4, have an inner lining of heat-insulating material to prevent them from receiving heat from the radiators and the lower surface.

Claims.

30 1. A levitation means carried by a floating body moving in an enveloping supporting medium for varying in advance of said body, the pressure of said enveloping medium in lines perpendicular to the plane of flight of said body, said means embodying a cylindrical moving surface disposed as a front surface of said body to divide said medium; and a prime mover carried by said body operatively connected with said cylindrical surface for moving the same so that the lower sector thereof is driven in a direction corresponding with the flight of said body.

2. A levitation means carried by a body 45 moving in an enveloping supporting medium for varying in advance of said body, the pressure of said enveloping medium in lines perpendicular to the plane of flight of said body, said means embodying a cylindrical moving surface disposed as a front surface of said body to divide said medium; and means carried by said body for radiating energy in the molecules of said medium juxtaposed to said surface.

55 3. A levitation means embodying two hollow cylinders; a connective continuous surface structure uniting in service relation said cylinders, said structure being shaped in correspondence with the pressures on said

ture is poised; means for transmitting to the surrounding medium energy acting perpendicular to the plane of the axes of said cylinders; and means for moving said cylinders through said medium.

4. A levitation means embodying two hollow cylinders; a connective continuous surface structure uniting in service relation said cylinders, said structure being shaped in correspondence with the pressures on said structure of the medium in which said structure is poised; means for transmitting to the surrounding medium in advance of said cylinders, an energy acting perpendicular to the plane of the axes of said cylinders; and means embodying a propulsion apparatus for moving said cylinders through said medium.

5. A levitation means embodying two hollow cylinders; a connective continuous surface structure uniting in service relation said cylinders, said structure being shaped in correspondence with the pressures on said structure of the medium in which said structure is poised; a propelling mechanism for 85 moving said cylinder through said medium, said mechanism embodying a prime mover and a propeller operatively connected therewith; and a transmission means operatively connecting said cylinders and said prime 90 mover for imparting to said cylinders an axially rotary movement, the lower sectors of said cylinders being moved in a direction corresponding with the line of flight.

6. A levitation means embodying a plurality of hollow cylinders; a connective continuous surface structure uniting in service relation said cylinders, said structure being shaped in correspondence with the pressures on said structure of the medium in which 100 said structure is poised; a propelling mechanism for moving said cylinders through said medium, said mechanism embodying a prime mover and a propeller operatively connected therewith; a transmission means 105 operatively connecting said cylinders and said prime mover for imparting to said cylinders an axially rotary movement, the lower sections of said cylinders being moved in a direction corresponding with the line of 110 flight; and means manually controlled for varying the rate of rotation of said cylinders for varying the levitation thereof.

Signed at Jersey City in the county of Hudson and State of New Jersey this 13th 115 day of October A. D. 1915.
